UNITED STATES PATENT OFFICE

ERNEST HOPE, OF LEICESTER, ENGLAND, ASSIGNOR TO UNITED SHOE MACHINERY CORPORATION, OF PATERSON, NEW JERSEY, A CORPORATION OF NEW JERSEY

FINISHING TOOL

Application filed January 12, 1929, Serial No. 332,203, and in Great Britain January 17, 1928.

This invention relates to finishing tools and is herein illustrated as embodied in a buffing roll of a type employed extensively in the manufacture of boots and shoes. The 5 invention is, however, applicable to tools of other types and designed for performing other operations.

In rolls of the type above mentioned the abrasive material is usually supplied in the 10 form of an abrasive sheet, such as sandpaper, which is wrapped around the roll and constitutes an abrasive cover therefor. It has been customary to hold such an abrasive cover in place upon the roll by 15 a series of paper-clamping hooks inserted radially into the body of the roll and arranged to be drawn down tightly against an edge of the abrasive cover to clamp it in place, the hooks being controlled through an 20 actuator disposed within the body of the roll. One such construction which has been used extensively and with a high degree of success is illustrated in United States Letters Patent 25 No. 1,014,094, granted January 9, 1912 upon an application of William A. Reed. One advantage of that arrangement resides in the fact that it provides a device for detachably securing the hooks to an actuator bar so that 30 broken hooks may be replaced without necessitating the disassembling of the roll as a whole.

One of the objects of the present invention is to provide a finishing tool of the type disclosed in the above-mentioned Letters Patent 35 with improved means for clamping and tensioning the abrasive cover. In accordance with this object, one feature of the invention consists in the provision of a pair of clamping jaws disposed respectively inside and out- 40 side of a yieldable cover which surrounds the roll body and which cushions the abrasive cover, the jaws being constructed and arranged to grip the yieldable cover as well as the abrasive cover to insure holding the 45 abrasive cover firmly without danger of cracking it.

In the illustrated construction, as in the construction disclosed in the Letters Patent referred to, the individual clamping hooks 50 are removably connected to the actuator bar

inside the roll by means of a locking member which may be reached from the exterior of the roll and moved in one direction or the other to release the hooks from or to lock them to the actuator bar. In accordance 55 with a further feature of the invention, the illustrated locking member plate or bar having recesses is made in the form of a steel plate having notches at its edge to allow the insertion of the hooks and arranged to be 60 moved longitudinally to engage the un- recessed portions of the locking bar in suitable lateral recesses in the shanks of the hooks thereby to lock each of the hooks to the actuator bar. 65

The above and other features of the invention, including details of construction, will now be more particularly described with reference to the accompanying drawing, in which,

Fig. 1 is a longitudinal view, partly in section, of an abrading tool embodying the invention in a preferred form;

Fig. 2 is an end view of the tool illustrated in Fig. 1;

Fig. 3 is an enlarged, fragmentary, transverse sectional view taken on the line III—III of Fig. 1;

Fig. 4 is a plan view of the hook shown in Fig. 3;

Fig. 5 is an end view of a device for holding the tool against rotation; and

Fig. 6 is a fragmentary plan view of the abrasive cover before being applied to the tool. 85

The illustrated abrading tool includes a cylindrical wooden core 10 (Fig. 1) surrounded by a resilient cover 12 of felt, the core 10 being supported at its ends by heads 14 carried upon a power driven shaft 16. 90 The core 10, the cover 12 and the heads 14 together constitute a roll body which is held against longitudinal movement with respect to the shaft 16 by means of collars 18. Cam grooves 20 are formed in the collars 18 for a purpose presently to be described. Concealed spring-pressed latches 22 are provided to prevent rotation of the roll body with respect to the collars 18 and the shaft 16 although the latches 22 may be released, to per- 100

mit, for a purpose later to be described, a limited rotation of the roll body with respect to the collars and the shaft, by means of a manually operated plunger 24 which is 5 slidably mounted in one of the collars 18 to a position where it may be depressed to release either of the latches 22. The structure so far described is substantially like the corresponding parts described and illustrated in 10 the above-mentioned Letters Patent No. 1,014,094, to which reference may be had for a more complete disclosure.

An outer covering 26 of any suitable soft 15 yieldable material is wrapped several times about the felt cover 12, to which it is secured by stitching or by other suitable means. Upon the outer cover 26 is carried an abrasive cover 28. The outer cover 26 softens the action of the abrasive cover upon the work and 20 adds materially to the life of the abrasive cover. It also assists clamping devices, later to be described, in holding the abrasive cover firmly upon the roll body without danger of cracking the abrasive cover.

25 The abrasive cover 28 is retained upon the roll body by means of clamping hooks 30 (Fig. 3) together with co-operating mechanism presently to be described. Each hook 30 consists of a substantially straight stem or shank 32 30 having a rectangular cross-section and a cover clamping jaw 34, the jaw extending substantially at a right angle to the shank. The hooks 30 are disposed along the length of the roll body, and they are moved into and out of 35 clamping position and also retained in clamping position by means of an actuator bar 36 (Figs. 1 and 3) which extends lengthwise of the roll body. The ends of the actuator bar 36 engage the respective cam slots 20 of the re- 40 spective collars 18, and the actuator bar 36 is thus normally held in cover clamping position by one of the latches 22. Upon unlatching the roll body and rotating it relatively to the shaft 16, the actuator bar 36 will be moved into and 45 out of clamping position, in the manner described in the aforementioned Letters Patent No. 1,014,094. The actuator bar 36 is recessed to provide a socket 38 to receive the shank 32 of each hook 30. For locking the hooks 30 to 50 the actuator bar 36 each of the shanks 32 has a recess 40 in the form of a rectangular notch which is engaged by a locking bar 42 formed of steel plate, the latter being slidably carried in a longitudinal recess or groove formed in 55 the actuator bar 36. The edge of the locking bar 42 which engages the notches 40 is itself notched away at 41 (Fig. 1) adjacent each of the shanks 32, so that a slight longitudinal movement of the locking bar 42 in the actuating bar 36, in one direction or the other, will 60 serve to lock or to unlock all of the hooks 30 simultaneously. The locking bar 42 may be shifted longitudinally to lock or unlock the hooks 30 by means of any simple tool, such as 65 a screw driver, which may be pushed against

either end of the locking bar 42. In order to permit access of the aforementioned tool, small openings 43 are provided in each of the collars 18 at the outer ends of the cam slots 20. In order to facilitate the positioning of the shanks 32 in their respective sockets 38 so that the notches 40 will register with the locking bar 42, an abutment 44 carried by the actuator bar 36 extends into each socket 38 and engages the base of each shank 32.

A yielding abutment in the form of a co-operating clamping jaw 46 (Fig. 3) is provided for each of the hooks 30. Each clamping jaw 46 is fixed upon the outer end of a plunger 48 which is guided for movement inwardly and outwardly of the roll body by a bushing 50 threaded in the core 10. Each plunger 48 is urged outwardly of the roll body by a helical spring 52 which surrounds the plunger 48 and is compressed between a shoulder 54 on the plunger and an internal flange 56 upon the base of the bushing. A stop bar 58 extends through a hole in each of the plungers 48 adjacent to the base thereof and, by engaging the base of each of the bushings 50, the stop bar 58 90 limits the outward movement of each plunger 48 so that the engaging face of each jaw 46 may be spaced from the axis of the roll body at substantially the same radial distance as the outer surface of the felt cover 12.

As shown in Fig. 3, the co-operating jaws 34 and 46 extend circumferentially of the roll body. The jaw 46 overhangs the top of the plunger 48, and the overhanging portion of the jaw 46 has a recess in the form of a hole 100 to permit the shank 32 to pass therethrough. Both jaws 34 and 46 have their engaging faces curved to conform to the general curvature of the roll body, the engaging face of the jaw 46 being also concave in a plane longitudinal of the roll body (Fig. 1) to form depressions into which the hook jaws 34 may snugly press portions of the abrasive cover 28 and the outer cover 26. The felt cover 12 has recesses 60 to accommodate the plungers 48 together with the respective jaws 46 and shanks 32. The outer cover 26 is not thus recessed, but has a small hole to accommodate each of the shanks 32, so that the outer cover 26, as above stated, is gripped between the 115 jaws 34 and 46 and thus serves to cushion the abrasive cover 28 at the points where the latter is clamped, providing a firm grip for the abrasive cover and minimizing any danger of tearing or cracking the latter at the 120 points where it is gripped. The hook jaw 34 is relatively narrow at its junction with the shank 32 (Fig. 4) and is relatively wide at its free end. The jaw 34 (Fig. 3) is also flattened out as its free end is approached. The 125 core 10 has a longitudinal recess 62 to accommodate the actuating bar 36.

The clamping hooks 30 are not spaced at uniform distances from each other, as has been customary in rolls hitherto manu- 130

factured, but are spaced closer together adjacent to the middle portions of the roll than at the ends of the roll, as shown in Fig. 1. By spacing the hooks more closely together adjacent to the middle portion of the roll, which is the portion that receives the greatest use, any tendency on the part of the abrasive cover to become loose and, therefore, to wear away rapidly at this portion is obviated, and the life of the cover is thereby prolonged.

The abrasive cover 28 is provided in sheet form and is wrapped about the roll body over the flannel cover 26 with one of the two edges of the abrasive cover overlapping the other. Before the abrasive cover 28 is applied to the roll body, a plurality of apertures 64 are formed in it in a line extending lengthwise of the sheet and adjacent to the edge which is to be overlapped. The apertures 64 are of sufficient size to permit threading the sheet over the widest portion of the hook jaws 34, and they are spaced to conform to the spacing of the hooks 30; that is, the apertures 64 which are adjacent to the middle portion of the sheet 28 are spaced closer together than the apertures 64 adjacent to the end portions of the sheet 28.

A pulley 66 secured to the shaft 16 is connected in the usual manner by a belt to any convenient source of power for driving the roll. In order to hold the shaft 16 against accidental movements when the roll is not in operation and while a fresh cover 28 is being applied to the roll, the pulley 66 has formed in its periphery a radially extending notch 68. A latch 70 is pivoted upon a stationary member 72, which may be a part of the machine frame, in such manner as to enable the latch 70 to be swung into engagement with the notch 68 and thus hold the shaft 16 and the roll stationary. The engaging end of the latch 70 is made sufficiently long to accommodate the notch 68 in any of the various positions of the pulley 66 in cases where the shaft 16 is reciprocated axially in addition to being rotated.

Assuming the roll to be in operation, and the abrasive cover 28 to be sufficiently worn to require replacement, the rotation of the roll is first stopped by manipulation of the usual clutch interposed between the pulley 66 and the source of power. The roll is rotated by hand to bring the notch 68 of the pulley 66 into a position for engagement with the latch 70, whereupon the latch 70 is swung into latching position to hold the shaft 14 against accidental rotation. The hooks 30 and plungers 48 are still in cover clamping position, as shown in Fig. 1. The abrasive cover 28 is now unclamped by rotating the roll body, as shown in Fig. 2, in a clockwise direction. The ends of the actuator bar 36 are forced outwardly by the cam slots 20, causing the entire actuator bar to move outwardly, until the ends of the actuator bar

engage the outer ends of the slots 20. The outward movement of the actuator bar raises all of the hooks 30. The plungers 48, being urged outwardly by the springs 52, follow the hooks 30 for a short distance but are stopped by the bar 58. The old abrasive cover 28 may then be removed from the roll. Any of the hooks 30 may be replaced at this time, if desired, by inserting a small tool, such as a screw driver, through the hole 43 in one of the collars 18 and pushing the locking bar 42 longitudinally until the notches in the engaging face of the locking bar are in register with the hook shanks 32. When new hooks have been inserted, the above-mentioned tool may be applied to the opposite end of the locking bar 42 through the hole 43 in the other collar 18 to push the locking bar into locking position. A new abrasive cover 28 is threaded, adjacent to one of its edges, over the hooks 30, and is then wrapped smoothly upon the roll with its other edge overlapping the first-mentioned edge. The roll is then rotated in a counterclockwise direction, as viewed in Fig. 2, until the ends of the actuator bar 36 engage the inner ends of the cam slots 20, whereupon the latch 22 operates to lock the roll in operative position. During the inward movement of the actuator bar 36 the hook jaws 34 move inwardly and clamp the abrasive cover 28 and the outer cover 26 against the plunger jaws 46. The inward movement of the hooks 30 forces the plungers 48 inwardly, and the abrasive cover 28 is, by reason of this inward movement of the cooperating sets of jaws, tensioned circumferentially of the roll, and the outer surfaces of the jaws 34 are brought within the general circumference of the roll body.

Having described my invention, what I claim as new and desire to secure by Letters Patent of the United States is:—

1. An abrading tool comprising a supporting body, a cover of yieldable material for said body, said body and said yieldable cover being adapted to support an abrasive cover upon said yieldable cover, and a pair of clamping jaws disposed respectively inside and outside of said yieldable cover, said jaws being constructed and arranged to grip both the abrasive cover and said yieldable cover and to move inwardly of said body to tension the abrasive cover.

2. An abrading tool comprising a supporting body, an inner cover of yieldable material for said body, an outer cover of yieldable material carried upon said inner yieldable cover, said body and said yieldable covers being adapted to support an abrasive cover, a clamping jaw supported by said body inside of said outer yieldable cover, said inner yieldable cover being recessed to accommodate said clamping jaw, and a second clamping jaw supported by said body outside of said outer yieldable cover, said clamping jaws being

constructed and arranged to grip the abrasive cover and said outer yieldable cover.

3. An abrading tool comprising a roll adapted to receive and support an abrasive cover, a plurality of clamping hooks, a plurality of abutment members for co-operating respectively with said clamping hooks to hold the abrasive cover upon said roll, means for yieldingly urging said abutment members outwardly, and a single member engaging all of said abutment members and constructed and arranged to limit the outward movement of said abutment members.

4. A rotary abrading tool comprising a roll body adapted to receive and support an abrasive cover, a plurality of hooks for holding the abrasive cover in place, said hooks each having a straight shank portion with a notch formed in a side of the shank portion, an actuator bar movable with respect to said body for tightening said hooks to clamp the abrasive cover to the body and for releasing said hooks to unclamp the cover, said actuator bar having a plurality of sockets to receive respectively the shanks of said hooks and having a straight groove extending substantially the length of the actuator bar and communicating with each of said sockets, and a straight locking bar slidably mounted in the groove in said actuator bar and engageable with the notches in said hooks to lock said hooks to said actuator bar.

5. A rotary abrading tool comprising a roll body adapted to receive and support an abrasive cover, a plurality of hooks for holding the abrasive cover in place, said hooks each having a shank portion with a recess therein, an actuator bar movable with respect to said body for tightening said hooks to clamp the abrasive cover to the body and for releasing said hooks to unclamp the cover, said actuator bar having a plurality of sockets to receive respectively the shanks of said hooks and having a longitudinal recess communicating with each of said sockets, and a locking bar adapted to enter the recess in said actuator bar and the recesses in said hooks to lock said hooks to said actuator bar, said locking bar having a plurality of recesses adjacent respectively to said hooks and which upon longitudinal movement of said locking bar with respect to said actuating bar will register with said hooks to unlock the latter simultaneously.

55 In testimony whereof I have signed my name to this specification.

ERNEST HOPE.

CERTIFICATE OF CORRECTION.

Patent No. 1,891,985.

December 27, 1932.

ERNEST HOPE.

It is hereby certified that error appears in the printed specification of the above numbered patent requiring correction as follows: Page 1, line 57, beginning with the word "plate" strike out all to and including "notches" in line 59, and insert instead "is made in the form of a plate or bar having recesses"; and that the said Letters Patent should be read with this correction therein that the same may conform to the record of the case in the Patent Office.

Signed and sealed this 8th day of August, A. D. 1933.

M. J. Moore.
